UNITED STATES PATENT OFFICE.

HENRY W. O'DOWD, OF JERSEY CITY, NEW JERSEY, ASSIGNOR TO WILLIAM M. CRANE COMPANY, A CORPORATION OF NEW YORK.

GAS RANGE.

Application filed June 6, 1921. Serial No. 475,182.

To all whom it may concern:

Be it known that I, HENRY W. O'Dowd, a citizen of the United States, residing at Jersey City, in the county of Hudson and State of New Jersey, have invented certain new and useful Improvements in Gas Ranges, of which the following is a specification, reference being had therein to the accompanying drawings.

10 The invention relates generally to apparatus for heating and cooking by gas, or other fluid fuel of analogous character. More specifically, it appertains to an improved construction and arrangement of the 15 various parts constituting the combustion chamber of a gas-stove, and its flue equipment.

One object of the invention is to provide a 20 range of the type set forth having a closed top adapted to be heated by an underlying centrally located burner, assisted by circumferentially disposed radiating elements, so arranged that the heat will be uniformly distributed in all directions.

A further object is the provision of a flue 25 surrounding the combustion chamber and through which the products of combustion are caused to pass, thus affording the closed top and the underlying radiating elements 30 additional time to absorb the heat units still remaining in the burning gases prior to their exit from the range.

Other objects and advantages of the invention will in part be obvious and in part 35 be more fully brought out in the following description.

The invention consists in the novel improvements, parts, combinations, and features of construction herein shown and 40 described.

In the accompanying drawings, which are referred to herein and form part hereof, are illustrated certain embodiments of the invention, the same serving in connection with 45 the description herein, to explain the principles of the invention.

Of the drawings:

Fig. 1 is a top plan view, partly in section, 50 of a gas-range embodying one form of the invention;

Fig. 2 is a front elevation, partly sectioned, of the same form of gas-range;

Fig. 3 is a vertical transverse section of the range shown in the two preceding views;

Fig. 4 is a top plan view of a gas-range 55 embodying the invention in a slightly different form; and

Fig. 5 is a vertical cross-section of the modified form of range shown in Fig. 4, 60 somewhat enlarged.

The body of the range, denoted as a whole by the reference numeral 11, may be of any suitable shape or design, but is preferably made square or rectangular as shown in the several views of the drawings hereto annexed. In both forms of the invention exemplified the range has an upper combustion chamber 12, which may extend the full length and width of the body 11, except a relatively narrow space around the said 70 chamber reserved for a flue 13. The chamber and the circumjacent flue are covered by a closed cooking top, which may consist of interfitting parts, as 14 and 15, laid upon the walls of the chamber and flue, respectively. A floor plate 12^a, attached to the outer walls of the range, completely covers the lower part of the chamber and flue. By preference, the combustion chamber and the surrounding flue are separated by common 80 walls 12^b which are formed with apertures 16, conveniently made in series, at regular intervals apart, to establish communication between the two.

In the form of range represented by Figs. 85 1, 2 and 3, secondary air to support combustion is supplied to the burner through a channel or passage 17 provided between the floor plate 12^a and a duplicate underlying plate 17^a spaced therefrom. The air 90 enters the passage 17, preferably, through a series of inlet openings 18, made in either or both of the side walls of the body 11. One or more similar apertures, as 19, are formed in the floor plate 12^a of the combustion chamber to admit the air therein directly beneath the burner. The products of combustion, after passing through the flue 13, as before described, escape through an exit 21 formed in the rear wall of the 100 flue and opening into a pocket 22 at the back of the range that has an outlet 23 for connection to a chimney. A natural draught is thus effected through the range, which insures a positive heat circulation.

A Bunsen burner 25 is mounted approximately in the center of the combustion chamber 12. Preferably and as shown, this

- burner is of the multiple ring variety and adapted for the burning of gas, either natural or artificial. Therefore, the several rings in the burner have their respective stems 26 connected with air and gas mixers 27 disposed within suitable openings in the front wall of the range, and receiving the fuel-gas from feed-pipes 28, coupled to a manifold 29, and furnished with plug-valves 30. The rings of the burner are concentric as ordinarily made, and are positioned flatwise in a substantially central location within the combustion chamber, directly under the closed top before mentioned.
- 15 The burner 25 is mounted in a pan or shield 34, placed flatly on the floor plate 12^a of the combustion chamber 12, and formed on its upper face with projections 35, upon which the burner is seated at predetermined points. The central portion of the pan 34 is also provided with perforations 36 registering with the air inlet openings 19 in the floor plate 12^a, thus providing for the admission of the external air into the combustion chamber from the passage 17. The projections 35 keep the burner at the proper elevation to enable the air passing through these openings and perforations to flow freely under and up through the burner's 20 rings, where it promotes combustion of the gaseous fuel at the flame ports. However, the rings are maintained at a predetermined distance from the overlying closed top so that the flames issuing from the burner 25 ports, and fanned by the inflowing air, may impinge against the under side of the top in heating it in the desired manner.
- Around the burner 25, and the pan 34, is placed a bed or layer of refractory material 37, such as fire-brick, capable of absorbing heat and transmitting it by radiation. The material, as indicated in Figs. 1 to 3, is preferably made to extend throughout the entire area of the combustion chamber 12, with the exception of a central pit or recess in which the burner and pan are situated. Thus, the material forms a continuous bed extending inwardly from the inner sides of the flue 13, to and around the 45 burner-supporting pan 34. The bed or layer 37 is raised from the floor of the combustion chamber to center it vertically therein, and consequently leaves a hot air space 38 underneath in addition to the combustion space above. It rests at the outer and inner edges upon flanges 39 and 40 provided on the walls of the chamber 12 and the rim of the pan 34, respectively, and intermediately it is supported by fore and 50 aft rods 41 seated in wall-sockets, as 42. It will be noted that the pan 34 shuts off communication between the air inlet openings 19 and the space 38 beneath the bed of refractory material 37, so that the secondary air is prevented from entering the 55

combustion chamber except beneath the burner 25.

Owing to the height at which the bed of refractory material is laid inside the chamber 12, in the construction represented in Figs. 1-3, the flame ports of the burner 25 stand a little below the surface of the bed 37, and therefore the refractory material is cut obliquely, as at 45, to produce a sloping approach to the said surface, so that the flames and burning gases, assisted by the external air draught, will the more easily spread over the material during combustion. In favorable conditions, the surface of the refractory material is co-extensive with the area of flame spread, depending of course on gas-pressure. Inasmuch as the combustion chamber 12 is practically surrounded by the flue 13 and separated from the same by the intermediate walls or partitions 12^b, the refractory material necessarily collects much of the heat resulting from the gas consumption, and then in turn radiates it equally in all directions. The parts above and below the radiating material are thereby heated, and in particular the closed top which is exposed directly to the burner flames. The products of combustion entering the flue 13, through its series of apertures 16, are kept hot for a longer period or more intensely heated by virtue of the radiation, and the fuel-gas is more thoroughly consumed before the residuum reaches the outlet. The heat derived from the products passing through the flue is naturally imparted to the closed top, which is thus heated to its outermost margin although but a single burner is employed.

Figures 4 and 5 illustrate a range construction similar to that hereinbefore disclosed, but involving a modification in the manner of setting the refractory material. In this modified structure, the bed 37 rests directly upon the floor plate 12^a of the combustion chamber 12, and consequently the upper space between the bed and the top plate is enlarged so that a heavier burner may be used, if the size of the range will permit. However, the burner 25 employed in the modification is situated in a pit or recess provided therefor in the center of the bed 37, as in the previous case, although the flame ports lie above the surface of the refractory material, which extends from the pit or recess outwardly to the walls of the chamber 12.

In both embodiments of the invention herein described, the bed of refractory material is arranged so as to bear at opposite sides on the pan 34 wherein the burner is mounted, and consequently serves to stabilize the latter. Thus in Fig. 2, the material is shown resting upon a flanged portion 40 of the pan 34; and in Fig. 5, the pan is caught under the material, which

is suitably grooved and recessed to receive it.

Ovens 56 are provided in both forms of the range, as herein exemplified. In each 5 case, the products of combustion rise from the oven into a horizontal flue 57, extending under the air passage 17 below the combustion chamber 12, each oven being heated by a separate burner (not shown) and the 10 products ascending through apertures 58. The discharge is somewhat different, however, in these ranges. As indicated in Fig. 3, the products from the flue 57 are led directly into the pocket 22, through one or 15 more openings 59, whereas in Fig. 5, the arrows represent the products as passing from the flue 57 into the flue 13, through other openings, as 60.

The invention in its broader aspects is 20 not limited to the precise constructions shown and described, nor to any particular mode of construction by which the same may be carried into effect, as many changes may be made in the details without departing 25 from the main principles of the invention and without sacrificing its chief advantages.

I claim:

1. A gas-range including a combustion 30 chamber presenting apertured side and end walls, a closed top covering said chamber, a flue surrounding the chamber walls and in communication with said chamber through the apertures of its side and end walls, a 35 central burner, and a bed of heat-radiating material arranged between the burner and flue and adapted to disseminate the heat from said burner uniformly in all directions.

2. A gas-range comprising an inclosed 40 combustion chamber provided with an inlet for secondary air, a burner located in said chamber, a flue surrounding the chamber, communicating therewith at all sides, a bed of heat radiating material intermediate of the burner and said flue, and means 45 including an outlet for the products of combustion arranged to cause a draught from said inlet to the flaming burner, thence in all directions across the surface of said material, and through the flue to said outlet.

3. A gas-range including a combustion 50 chamber having an air inlet, a closed top covering said chamber, a flue extending around the chamber and communicating therewith at all sides, and a burner located within the combustion chamber and having flame ports approximately centered with relation to the flue.

4. A gas-range including a combustion 60 chamber having a localized air inlet formed in the bottom thereof, a burner located in said chamber above the air inlet, a closed top covering the chamber, a bed of radiat- 65 ing material surrounding said burner and

spaced from said top, and a flue circumscribing the combustion chamber and in communication therewith.

5. A gas-range including a combustion chamber, an exterior passage for secondary air extending thereunder, a surrounding flue in communication with the chamber, a burner mounted in the chamber, a bed of refractory material arranged between said burner and the flue, a closed top overlying the burner and said bed, and means for directing the air from the exterior air passage to the underside of the burner.

6. A gas-range including a combustion chamber having an inlet for secondary air, 80 a burner located above said inlet, a closed top covering the combustion chamber, a bed of refractory material disposed around the burner, a flue circumscribing the combustion chamber, and means for preventing the 85 secondary air from ascending into the space between the refractory material and the closed top without passing the burner.

7. A gas-range including a combustion chamber formed with an air inlet in its 90 bottom, a closed top covering said chamber, a burner therein, a bed of refractory material around said burner, a pan wherein the burner is mounted and apertured to register with the air inlet, and a flue 95 surrounding the combustion chamber and communicating therewith.

8. A gas-range including a combustion chamber formed in its bottom with a localized air inlet, a flue extending around said 100 chamber, a wall or partition separating the chamber and flue, said wall being apertured to admit the products of combustion into said flue at all sides of the combustion chamber, a closed top covering the chamber, 105 a burner mounted therein above the air inlet and a bed of refractory material laid between the burner and the separating wall and located below the apertured portion thereof.

9. A gas-range including a combustion chamber with an inlet for secondary air, a surrounding flue apertured to receive the products of combustion from said chamber and having an exit therefor, a closed top 115 covering the chamber, a burner, a bed of refractory material interposed between the flue and burner, an oven provided with a discharge adjacent the flue exit and having no other communication with the flue, and 120 a common outlet for the products issuing from the oven and flue.

10. A gas range including a closed cooking top, an underlying combustion chamber substantially coextensive with the cooking top and having an inlet for secondary air, a Bunsen burner located in said chamber, and means for preventing the secondary air from entering the combustion chamber without passing the burner.

11. A gas range including a combustion chamber having an outlet for secondary air, a flue for the products of combustion surrounding the combustion chamber and communicating therewith, a Bunsen burner located in said chamber, a closed top overlying the burner and covering the combustion chamber, and means for preventing any portion of the secondary air from entering the combustion chamber without passing the burner.

12. A gas range including a closed cooking top, an underlying inclosed combustion chamber substantially coextensive with the cooking top and having an exit for the products of combustion, a Bunsen burner located in said chamber, a secondary air channel located outside of said chamber, and means for directing the secondary air from said air channel to the underside of the burner.

13. A gas range including a closed cooking top, an underlying inclosed combustion chamber substantially coextensive with the cooking top and having an exit for the products of combustion, a Bunsen burner located in said chamber, and inlet openings formed in the bottom of the chamber and located solely beneath the burner for admitting secondary air to the underside of the burner.

14. A gas range including an inclosed combustion chamber having an exit for the products of combustion, a Bunsen burner located in said chamber, inlet openings formed in the bottom of the chamber and located solely beneath the burner for admitting secondary air to the underside of the burner, and a shield underlying the burner and formed with air openings registering with those in the bottom of the combustion chamber, the said shield serving to prevent the entrance of secondary air into the combustion chamber without passing the burner.

15. A gas range including an inclosed

combustion chamber having an exit for the products of combustion, a Bunsen burner located in said chamber, a shield underlying the burner and partly covering the same and formed with openings for secondary air, and means for preventing the entrance of secondary air into the combustion chamber except through the openings formed in the burner shield.

16. A gas range including a closed cooking top, an underlying inclosed combustion chamber substantially coextensive with the cooking top and having an exit for the products of combustion, a Bunsen burner located in said chamber, a secondary air channel extending along the underside of the combustion chamber, and openings formed in the bottom of said chamber and arranged solely beneath the burner for admitting secondary air from the air channel to the underside of the burner.

17. A gas range including an inclosed combustion chamber having an exit for the products of combustion, a Bunsen burner located in said chamber, a secondary air passage extending along the underside of the combustion chamber, and a shield underlying the burner and partly covering the same and formed with openings communicating with the secondary air passage.

18. A gas range including an inclosed combustion chamber having an exit for the products of combustion, a Bunsen burner located in said chamber, an oven located beneath the combustion chamber, and a secondary air passage extending between the combustion chamber and the underlying oven and communicating with the former through openings formed in the bottom thereof.

In testimony whereof, I have affixed my signature hereto.

HENRY W. O'DOWD.
